UNITED STATES PATENT OFFICE.

JOSEPH C. COULOMBE, OF LOWELL, MASSACHUSETTS, ASSIGNOR TO HEINZE ELECTRIC COMPANY, OF LOWELL, MASSACHUSETTS, A CORPORATION OF MASSACHUSETTS.

CARBURETER.

1,201,220.

Specification of Letters Patent.

Patented Oct. 16, 1916.

Application filed February 26, 1914. Serial No. 821,109.

To all whom it may concern:

Be it known that I, JOSEPH C. COULOMBE, a citizen of the United States, and a resident of Lowell, in the county of Middlesex 5 and State of Massachusetts, have invented certain new and useful Improvements in Carbureters, of which the following is a full, clear, and exact description, whereby any one skilled in the art may make and use 10 the same.

The invention relates to carbureters and more particularly to a carbureter for liquid hydro-carbon such as may be applied to internal combustion engines for automobiles, 15 boats, etc.

It relates more specifically to the valves and adjustments for a carbureter of the compensating type in which a properly attenuated mixture is automatically secured 20 for all ranges of speed of the engine no matter what adjustment has been made for temperature.

It is desirable in a device of the character herein referred to to provide adjustments 25 which will maintain mixtures of definite character for varying temperature conditions, as, obviously, the valves must be adjusted for cold weather as well as hot and whether the adjustment is made for cold 30 weather conditions or for hot weather conditions, it is essential that in the speed ranges from low to high speed, definite conditions of mixture should be maintained.

The present invention contemplates the 35 use of a valve seat and valve for controlling the flow of "fuel" in which the area of opening between the valve and valve seat for any adjustment will produce an automatic operation which will give a proper attenuation 40 of mixture for all speeds.

It has been common practice to use a cylindrical valve opening and control it with a tapered needle valve. This needle valve has been raised automatically to provide greater and greater opening through the nozzle as the speed of the engine is increased. Of course, it has also been necessary to adjust such a needle valve for variable conditions of temperature. When the 50 weather is warm, the tapered needle must normally rest very close to its seat while in

cold weather it must be adjusted away from its seat to give an initially larger opening. When such a valve is thus adjusted, the adjustment may be a proper one for low speeds 55 but on high speeds, as the taper of the needle rapidly decreases as it is raised, the mixture will not be rich enough.

As hereinafter described, there is employed in the present invention an arrangement of valve stem and valve in which the narrowest portion of the taper of the parts is normally closed or nearly closed for low speeds and the wider portions of the taper become effective for high speeds. With this 60 arrangement, the flow of "fuel" for low speeds occurs when the valve spindle is in a position nearly closing the narrowest end of the taper. An adjustment of the parts for low speed will always give a proper 65 richness of mixture for high speeds. In fact, the richness of the mixture may be proportionately increased. Such a condition is impossible with a tapered valve stem and cylindrical valve opening. 70

The arrangement and control of the tapered valve, as hereinafter set forth, is an important feature of the invention as it provides an accurate means for regulation necessary for changes in temperature. The 75 arrangement will give a sufficiently rich mixture at low speeds and will give a much larger increase of "fuel" at high speeds and such an increase as is necessary for proper operation. 85

The invention also contemplates an adjustment which will permit adjusting the fuel valve without changing the relative position of the air valve and its seat so that one adjustment is all sufficient for the oil 90 valve and the air valve.

The invention also contemplates a special arrangement of parts for starting the engine in which there is a choke-valve which will ordinarily cut off the air inlet and provide 95 a direct connection with the fuel supply and will automatically upon release, cut off the fuel supply and open the air inlet. This arrangement is particularly efficacious in starting a motor in cold weather. 100

The invention also relates to details hereinafter more fully defined.

It is the object of the invention to provide a simple compact form of carbureter which may be readily adjusted for varying temperatures and which will produce a properly attenuated mixture at varying speeds of the engine for any given adjustment.

A still further object is to provide for an adjustment of the fuel valve without in any way disturbing the adjustment of the air valve and a still further object is to provide an automatically acting choke valve which in closed position will provide a shut-off for the inlet of air and open the inlet for the fuel and when released, will automatically assume a position of cut-off with reference to the fuel and will be open to the air.

Referring to the drawings: Figure 1 is a top plan view of the device. Fig. 2 is a sectional view on the line 2—2 of Fig. 1. Fig. 3 is a cross-sectional view on the line 3—3 of Fig. 1. Fig. 4 is a detail view of the combined air and oil valve and supporting parts. Fig. 5 is a detail sectional view similar to Fig. 2 illustrating a modified form of tapered valve. Fig. 6 is a diagrammatic view illustrating the operation of the ordinary type of needle valve. Fig. 7 is a diagrammatic view illustrating a valve of the present invention. Fig. 8 is a detail view of a horizontal section.

In the accompanying drawings, the device is shown in a convenient form although it is to be understood that its details in the arrangement and design of parts may be modified to a considerable extent without departing from the spirit or intent of the invention.

Referring to the drawings, the numeral 1 denotes the body of the carbureter which has a circular base-plate 2 against which rests the upper edge of a float feed bowl 3 which provides a float-feed chamber 4. This bowl 3 is held against a shoulder 5 of a dependent portion 5^a of the carbureter body by a nut 6.

Within the float-feed chamber 4 there is a float 7 which, through a pivoted lever 8 controls an inlet valve 9, which, as illustrated, is of the tapered form and normally rests against a seat 10 when the float chamber 4 has received a sufficient quantity of fuel to raise the float 7.

The valve 9 controls the fuel inlet 11 which is connected with any suitable source of supply. Centrally arranged with reference to the carbureter body and float-feed chamber is a bushing 12 which has at its lower end an upwardly extending tapered opening 13 which is connected through a passage 14 with the float-feed chamber 4. This bushing has at its lower end the usual draw-off valve 15. Connected with the tapered opening 13 is a passage 16 in the dependent portion 5^a, which terminates in the venturi 17. This venturi is of curved form

offset from the center of the body of the carbureter in such manner as not to interfere with the concentrically arranged valve stem and appurtenant parts. This venturi opens on opposite sides of a central partition 17^a which divides the air inlet side from the mixing chamber 27. Thus the incoming air is all drawn through the venturi during low suction actions.

The exterior of the bushing 12 is reduced in diameter to form a chamber 18 and this, at its upper end, through a suitable duct 18^a connects with the atmosphere so that there is an equalization of atmospheric pressure throughout the device wherever the oil supply is present.

Extending through the bushing 12 is a valve-stem 19, the lower end 20 of which rests at or near the bottom of the beveled opening 13 while the upper end is connected with the air valve 21. This air valve 21 rests upon a seat 22 formed in a dependent cage 23. The cage 23 is arranged preferably integral with an adjusting plug 24 which has an inferior bore 25 serving as a guide for the upper end 26 of the valve spindle. The lower end of the cage 23 projects through an opening in a partition wall 21 which with the wall 17^a divides the inlet side of the carbureter from the mixing chamber 27.

Incoming air on low suction passes through the venturi 17. When the suction is materially increased, the valve 21 is raised from its seat 22 and air may then pass therethrough to be mixed with the air which is picking up fuel from the venturi. Both the current of fuel-laden air passing through the venturi and that passing through the open valve 21 are thoroughly mixed in the chamber 27 from which they are passed on, beyond the throttle valve 28. The arrangement of the partitions dividing the inlet side and the mixing side 27 are best illustrated in Figs. 2, 3 and 8.

With the above arrangement it is obvious that as the plug 24 is adjusted, the dependent cage 23, seat 22 and air valve 21 are moved as a unit and the valve stem 19 is raised or lowered so that its lower end 20 may regulate the opening through the beveled valve seat of the bushing 12.

To make adjustments for variations in temperature and consequent variations in the position of the valve stem 19 and tapered valve seat, the screw plug 24 may be raised and lowered, thereby increasing or decreasing the amount of fuel which will pass from the float feed chamber 4 through the passage 14, tapered chamber 13, opening 16 and venturi 17 to the mixing chamber.

It is of course quite obvious that the bushing 12 might be adjusted axially with reference to the valve stem in lieu of adjusting the screw plug 24 although it is preferred to

adjust by the means above described, and illustrated.

In Fig. 3, the mixing chamber 27 is illustrated as having its outlet controlled by a 5 throttle valve 28 of ordinary type. This valve is in turn controlled by a lever 29 which may be actuated by any suitable connection. At a point substantially diametrically opposite the valve 28, there is arranged a choke valve 30 which in normal 10 position is held open by a spring 31 suitably attached to its spindle. This choke-valve has the lower end 32 of its stem provided with a passage 33 which, when the valve is 15 in closed position with reference to the inlet 34 registers with a passage 35 which extends into the float-feed chamber below the level of the fuel and also registers with a passage 36 which extends directly into the venturi 20 17. The purpose and function of the choke-valve 30 is to provide for easy starting.

A wire or suitable connection extends from the valve 30 to a convenient position so that upon a pull of the wire or connection, 25 the valve will be closed as to the air inlet opening 34 and will be open as to the passages 35, 33, 36, so that as the engine is cranked, the suction will draw fuel directly from the float-feed chamber into the venturi 30 17. Upon a release of the wire or connection of the valve 34, the spring 31 will turn it to normal position, shutting off the passages 35, 36 and opening the air inlet 34.

It will be observed that the vertical inlet 35 to the venturi 17 is arranged at one side of the bushing 12 and that the venturi is slightly offset with reference to the bushing so that said bushing with the valve stem 19 and appurtenant parts are all formed 40 through the central part of the body of the carburetor and do not separate the venturi. It will also be observed that there are a plurality of the passages 14 one of which is illustrated in full lines and one in dotted 45 lines in Fig. 2. It is preferred to have these passages arranged substantially 90° apart. Thus the static head and rate of flow from the float-feed chamber will be the same under all ordinary conditions, regardless of the 50 tip of the automobile or boat or other device on which the device is used. This arrangement provides for proper feed either on side tip or on all grades.

In Fig. 5, the parts are the same as illustrated in the figures heretofore described with the exception of the arrangement of the lower end of the valve 50. This valve stem 50 is of tubular form and is provided with an interior bore 51, the larger end of which 60 is at the bottom of the valve stem. Projecting up into the tapered valve stem is a stand-pipe 52 which is connected through passages 53 with the float-feed chamber 14.

The fuel passes from the float-feed chamber 65 through the passage 53, upper end of the

stand-pipe 52 into the hollow valve stem 50, thence through the opening 54 to passages 55, 56 to the venturi 57.

It is, of course, immaterial whether the taper is in the bushing with a cylindrical valve stem or a tapered hollow valve stem is employed with a cylindrical stand-pipe, provided the closing of the valve occurs at the narrowest diameter of the taper and gradually increases as the air valve raises 70 and the speed of the engine is increased. In either event, as the air valve by its movement opens the fuel valve, there is an outlet opening, ever increasing in diameter. This obviously, in practice, is quite different from the type of valve wherein there is a cylindrical opening into which extends a needle valve. This difference is clearly illustrated in the diagrammatic illustration of Figs. 6 and 7. In Fig. 6 the ordinary type of cylindrical opening and needle valve is employed. Assume that owing to changes of temperature or other causes, it is necessary to adjust the needle valve upward with reference to the cylindrical valve tube a distance $a-b$. This adjustment would provide a difference in area equal to the difference of the diameter of the stem at the point a and the diameter of the stem at the point b as compared with the cylindrical opening into which it projects. The needle valve tapers to a sharp point and of course as the engine runs at high speed, the lower end of the needle valve is brought up to a point adjacent to the upper end of the cylindrical opening. It follows therefore that having adjusted the distance $a-b$ for low speeds, the portion $c-d$ of the valve would be in play at high speeds. Comparing the difference in area of opening due to the difference in the taper of the valve 95 at the point c and the taper of the valve at the point d , it is apparent that the difference in area between the points c and d is much less than the difference in area for the points a and b . It follows therefore that at high 100 speeds there will be too small a flow of "fuel" although the adjustment might have been perfectly made for the proper flow at low speeds which latter adjustment is represented by a, b .

Comparing the above condition with Fig. 7, it is apparent that there is a reversal of conditions.

Assuming that a cold weather adjustment is made by raising the valve stem from the point b to the point a , this will give a variation in valve opening equal to the difference of the area at the point b' and the point a' . As the valve spindle is raised under high speed to the point so that c', d' correspond with a', b' , the opening of the valve will correspond to the difference in area at the point a' and the point d' . Obviously, the difference in area between c', d' is greater than the difference between a', b' . Therefore, a 110 120 125 130

richer mixture will be secured at high speed than in the case of the high speed position of the needle valve illustrated in Fig. 6. In other words, an adjustment of the valve 5 stem of Fig. 7 which will secure proper flow for low speed will maintain a proper mixture of richness at high speeds, whereas with the needle valve of Fig. 6, a proper adjustment to secure the desired richness of mixture at low speed will upon high speeds give a mixture lacking in proper richness.

Obviously, various details may be made to suit the exigencies of any particular type of construction required and the same valve arrangement 15 may be applied in various manners.

What I claim as my invention and desire to secure by Letters Patent is:

1. In a carbureter having an air inlet, a 20 mixing chamber and an outlet therefrom, a partition dividing the inlet from the mixing chamber, a venturi passage opening on both sides of said partition and extending below the partition, a fuel duct for said venturi and a float feed chamber supplying fuel to said duct and venturi.

2. In a carbureter having an air inlet, a 30 mixing chamber and an outlet therefrom, a partition dividing the inlet from the mixing chamber, a venturi passage having an opening on both sides of the partition and a depressed passage passing below the partition and forming a receptacle for fuel, an air valve intermediate the inlet and mixing chamber and centrally disposed with reference thereto and arranged at one side of the venturi passage, a fuel valve controlled by said air valve, a float feed chamber supplying fuel to said fuel valve and a duct connecting the fuel valve and venturi.

3. In a carbureter having an air inlet, a 35 mixing chamber and an outlet therefrom, a partitioning wall arranged between the inlet and mixing chamber, a perforation formed through a portion of the partitioning wall in substantially the axial line of the inlet and outlet, an air valve normally closing said opening, a venturi passage curving about the partitioning wall and arranged at one side of the central line of the valve, said venturi having openings on opposite sides of the partition to the inlet and mixing chamber respectively, a fuel valve connected with and controlled by the air 45 valve, a float feed chamber communicating with said fuel valve and a duct intermediate the venturi and fuel valve.

4. In a carbureter having an inlet, a mixing chamber and an outlet therefrom, a partitioning wall dividing the inlet from the mixing chamber, a valve seat formed in a portion of the partitioning wall and an air valve seated therein, a stem for said valve terminating in a fuel valve, a bushing surrounding said valve stem and valve, a fuel

chamber arranged about said bushing and having a duct opening to the atmosphere, a float feed chamber feeding fuel to said valve and fuel chamber, a venturi forming a receptacle for fuel having its bottom slightly 70 below the fuel level of the float feed and fuel chamber and a duct connecting said venturi with the fuel chamber.

5. In a carbureter having an inlet, a mixing chamber and an outlet therefrom, a partitioning wall dividing the inlet from the mixing chamber, a venturi passage passing about the partition and opening on opposite sides thereof to the inlet and mixing chambers respectively and at one side of a common central line of the inlet and outlet, an air valve arranged in the partitioning wall and centrally of the common axial line of the inlet and outlet, a hollow valve stem connected therewith and having a tapered opening at its end, a cylindrical fuel valve projecting into said tapered opening, a float feed chamber communicating with said fuel valve and a duct communicating with the hollow valve stem and the venturi.

6. In a carbureter having an inlet, a mixing chamber and an outlet therefrom, a partitioning wall dividing the inlet from the mixing chamber, a venturi passage extending about the partition at one side of 95 its center and opening on opposite sides thereof to the inlet and mixing chamber respectively, an air valve closing an opening in the partitioning wall, a fuel valve and nozzle controlled by the air valve, said fuel 100 valve and air valve centrally located with reference to the carbureter and with the venturi at one side thereof, a float feed chamber centrally arranged with reference to the fuel valve, a duct connecting said float feed 105 chamber with the fuel valve, a fuel chamber surrounding the fuel valve and open to the atmosphere, a venturi duct connecting said chamber and the venturi and a duct connecting the fuel chamber and fuel valve.

7. In a carbureter, a body-part having an inlet, a mixing chamber and an outlet, a partitioning wall between the inlet and mixing chamber, a venturi passage curving below said partitioning wall at one side of the 115 center thereof, and opening into the inlet passage and the mixing chamber, a central dependent member extending below the main body of the carbureter and centrally disposed with reference thereto, a fuel nozzle 120 centrally arranged in said dependent member, a float feed chamber concentrically arranged about said dependent member and communicating with the fuel nozzle, an air port through the partitioning wall, an air 125 valve seated therein and having a stem controlling the fuel nozzle, said valve and stem having an axis coinciding with the central axis of the dependent portion and a duct connecting the venturi with the fuel nozzle.

8. In a carbureter having an air inlet, a mixing chamber and an outlet therefrom, a partitioning wall dividing the inlet from the mixing chamber, a venturi passage extending about the partition and opening into the inlet and mixing chamber respectively, a valve for closing the inlet, a fuel passage controlled simultaneously with a movement of the air valve and fuel ducts connecting said fuel passage, venturi and a fuel supply. 10
